UNITED STATES PATENT OFFICE.

CLEVELAND G. TERRY, OF LOS ANGELES, CALIFORNIA.

STOVE.

1,341,623.

Specification of Letters Patent.

Patented May 25, 1920.

Application filed December 30, 1918. Serial No. 268,814.

To all whom it may concern:

Be it known that I, CLEVELAND G. TERRY, a citizen of the United States, residing at Los Angeles, county of Los Angeles, and 5 State of California, have invented a certain new and useful Improvement in Stoves, of which the following is a specification.

My invention relates to a heating device and has especial reference to stoves of the 10 type generally known as "air tight stoves", an object of the invention being to provide a simple, economical and efficient stove, which will produce a continuous circulation of air in a room and thus prevent the accumulation of noxious gases and odors.

Other objects of the invention are to provide a stove which will at all times evenly distribute the heat, and in which the heat may always be under perfect control, and 20 the life of the stove be materially prolonged by avoidance of spasmodic temperatures which, in stoves of present construction, causes their quick deterioration and ruin.

Other objects will appear from the sub-25 joined specification, in connection with the accompanying drawing, which represents a preferred form of embodiment of the invention, and in which—

Figure 1 is a vertical sectional view.

30 Fig. 2 is a horizontal section on line 2—2, Fig. 1, and

Fig. 3 is a plan view of the inclosure, showing the air control therein.

The stove consists of a body 1, having a 35 top 2, stove pipe 3, and bottom 4, upon which is built the fire. The bottom 4 is provided with two oppositely disposed openings 5 and 6, communicating with passageways or air vents 7 and 8, formed preferably by semi-40 circular plates 9 and 10, respectively riveted or otherwise fastened to the bottom and walls of the body 1 of the stove. Over the top of the passageway 7, is preferably placed a deflector 11, for directing the air down-45 wardly upon the fire, and the plate 10, forming the passageway 8, is, by preference disposed under the stove pipe 3, for obvious reasons.

Onto the underside of the bottom 4 is fastened an inclosure 12, the top of which is covered by the bottom 4, and the bottom of which inclosure 12 is provided with an aperture 13, and concentric grooveways 14 and 14'. One wall of the inclosure is provided 55 with slots 15 and 15', through which extend the branches 16 and 16' of a damper or air

control 17, which branches are seated, and are operable in said grooveways 14 and 14', by a handle 18, to control the passage of air entering through said aperture in the bottom of said inclosure to either the passageway 7 or 8 or both, as desired.

When the damper is in central position or that shown in Fig. 3, both branches thereof extend approximately half way across the 65 inclosure in which they are contained, permitting thereby the circulation of air through both passageways 7 and 8, and maintaining the fire in the stove at an even temperature and insuring a uniform circulation of air 70 and heat radiated from the stove in a room, when the fire is well started.

When starting the fire, however, the damper 17, is moved preferably to close entirely or partially communication between 75 the opening 13 and the passageway 8, such operation establishing communication between the opening 13 and the passageway 7. After the fire is started sufficiently, the damper 17 may be moved to central position, as shown in Fig. 3, or may be moved to close entirely communication between the aperture 13 and the passageway 7 and establish communication between aperture 13 and passageway 8, thereby closing off the 85 air from the fire except sufficiently for a steady, uniform and ideal glow, particularly where coal is the fuel, and at the same time creating a healthful circulation of heated air through a chamber. The cold air then 90 enters through the aperture 13 and passes upwardly through the passageway 8, and then into the stove pipe with the radiated heat from the stove. The stove pipe being thus kept cool, prevents the creation of a 95 vacuum, which would cause a high draft and produce an intense combustion of the fuel, with ensuing detriment to the stove. Hence by means of this damper, an even combustion of fuel, a perfect radiation of 100 heat and a steady circulation of air may be had, with a resultant economy in fuel.

What I claim is:—

1. A stove comprising a closed body having a stove pipe and a bottom provided with 105 oppositely disposed inlets, said body provided with oppositely disposed air vents in communication with said inlets and extending to near the top of and having free communication with the interior of the stove 110 body, one of said vents disposed approximately in line with but spaced from said

stove pipe, and means to regulate the supply of air to both said air vents or positively to prevent the passage of air to one of said vents while permitting it to the other.

5 2. A stove comprising a closed body having a stove pipe and a bottom provided with oppositely disposed inlets, means within said body forming vertical passageways communicating with the inlets in said bottom, both of said passageways extending to near the top of and in free communication with the interior of said body, one of said passageways disposed approximately in line with said stove pipe, a deflector above the other of said passageways, an open inclosure fastened to the underside of the bottom of said body and communicating with the inlets therein and said passageways, said inclosure having a central air inlet, and a vertically disposed air controlling means in said inclosure having two branches and extending approximately half way across said inclosure and operable about said central aperture to direct the air to either one or the other of said passageways or control the ratio of air to both passageways.

20 3. A stove comprising a closed body hav-

ing a stove pipe and a bottom provided with oppositely disposed air ports, said body provided with oppositely disposed air vents in communication with said ports and extending to near the top of and having free communication with the interior of said body, and one of said vents disposed approximately in line with said stove pipe, an inclosure fastened to the underside of the bottom of said body and communicating with the ports therein, and with said vents, said inclosure having a central air aperture, and a vertical air control in said inclosure having two branches extending normally to approximately the center of said inclosure and operable about said central aperture to regulate the supply of air to both said air vents or positively to prevent the passage of air to one of said vents while permitting it to the other.

In testimony whereof I have set my hand in the presence of two witnesses.

CLEVELAND G. TERRY.
